UNITED STATES PATENT OFFICE.

JOHN GEORGE URSTADT, OF NEW YORK, N. Y.

GARMENT-SUPPORT.

1,228,266.

Specification of Letters Patent. Patented May 29, 1917.

Application filed November 18, 1916. Serial No. 132,142.

To all whom it may concern:

Be it known that I, JOHN GEORGE URSTADT, a citizen of the United States, residing at New York, in the county of Bronx and State 5 of New York, have invented new and useful Improvements in Garment-Supports, of which the following is a specification.

The present invention relates to improvements in garment supports.

10 In carrying out the invention it is my purpose to produce a garment support designed for men's wear wherein the same may be easily and quickly connected with the waistband of the trousers and which is 15 adapted to engage with a suitable strap upon the inner garment or drawers of the wearer and which is also adapted to engage with the belt, so that the said belt and inner garment will be retained in proper 20 position with relation to the trousers of the wearer.

It is a further object of the invention to produce a device of this character which is constructed of a single strip of resilient 25 material having its ends so bent as to effectively engage with the strap of the inner garment, to also engage with the waistband of the trousers and which is provided with tongues that frictionally insure the 30 proper engagement of a removable belt with the trousers.

With the above and other objects in view the improvement resides in the construction, combination and arrangement of parts set 35 forth in the following specification and falling within the scope of the appended claim.

In the drawing:

Figure 1 is a perspective view illustrating the application of the improvement, the 40 device being illustrated as applied to the strap upon the inner garment,

Fig. 2 is a perspective view looking toward one of the ends of the device,

Fig. 3 is a top plan view of the construction illustrated in Fig. 2,

Fig. 4 is an elevation illustrating the manner in which the device is arranged upon the outer garment.

Preferably but not necessarily, and as 50 illustrated in Fig. 4 of the drawing, the improvement is secured to the outer garment 1 by forming the said outer garment with a pocket, but it is here to be stated that the

device which is constructed of resilient material may embody sufficient tension as to 55 be self-sustaining upon the garment.

The improvement, as disclosed by the drawing, is constructed from a single strand of suitable wire and comprises a body portion 2, which, as illustrated in Fig. 4, is arranged within the mentioned pocket, the same for convenience being designated by the numeral 3. The body 1, at the ends thereof, is bent upon itself to provide a substantially U-shaped loop 4, and the lower 60 or connecting member for the arms of this loop are adapted to receive the threads 5 which serve additionally to secure the said device to the outer garment 1. The outer arm 6 of the loop 4 is bent upon itself to 65 provide a tongue 7 which is also U-shaped and which is arranged in a plane with the loop 4 but which may be, if desired, arranged at a slight inclination to the said loop 4. The outer member provided by the 70 tongue 7 and which, for distinction, is indicated by the numeral 8 is bent upon itself, at an angle, approximately forty-five degrees with respect to the plane of the tongue 7 forming the inner member 9 of a clip 10. 75 The clip 10 is also U-shaped in side elevation, and the outer arm 11 thereof has its end formed with a head or enlargement 12. The clip 12 is adapted to have frictionally 80 engaged between the arms of the same a belt 13, while disposed to be engaged between the arms or legs of the loop 4 and to be also engaged by the inner arm 8 of the tongue is a strap or band 4 that is secured to the inner garment or trousers 15. 85

The strap 14 is centrally secured to the inner garment 15 as indicated by the numeral 16 and the ends of the said strap are likewise secured to the inner garment, as indicated by the numeral 17. 90

From the above description, taken in connection with the accompanying drawing, the simplicity of the device, as well as the advantages thereof will, it is thought, be perfectly apparent to those skilled in the 100 art to which such invention appertains without further detailed description.

Having thus described the invention, what I claim is:

In a device for the purpose set forth, a 105 member constructed of resilient material

having its ends bent to provide substantially U-shaped loops which are disposed at a right angle to the body, the outer end members of the said loops being bent upon themselves to provide U-shaped tongues disposed in a plane with the loops, the outer members of the said tongues being bent upon themselves

to provide U-shaped clips, the said clips being disposed at substantially a right angle with respect to the tongue and to the loop, 10 and the outer member of the said clips being formed with enlargements providing heads.

In testimony whereof I affix my signature:
JOHN GEORGE URSTADT.
